UNITED STATES PATENT OFFICE

KENT S. CLOW, OF LAKE FOREST, AND JOHN A. BYERS, OF EVANSTON, ILLINOIS,
ASSIGNORS TO JAMES B. CLOW & SONS, OF CHICAGO, ILLINOIS, A CORPORATION OF
ILLINOIS

TRIP-LEVER BATH WASTE MECHANISM

Application filed December 24, 1928. Serial No. 333,204.

This invention pertains to plumbing fixture waste mechanisms and more particularly to a waste plug construction and mechanism for operating it, adapted for use in connection with various types of plumbing fixtures such as wash basins, sinks, tubs and other devices of a similar character.

One of the primary objects of the invention is to provide a novel waste plug so constructed that it may be substantially permanently secured to the fixture and yet may easily be raised to permit water to escape from the fixture or lowered to close the outlet orifice of the fixture against egress of water. In this connection the construction is such that the outlet plug may be raised only partially to permit the inspection of the outlet and its connections or the insertion of tools or other means into the orifice for any purpose.

Another object of the invention is to provide a novel arrangement for operating a plug of the aforementioned character from a position or place remote from the outlet orifice as, for instance, the overflow connection of the fixture.

Another object of the invention is to provide a novel type of combination escutcheon plate and overflow orifice.

Many other objects as well as the advantages and uses of the invention will be or should become readily appreciated and understood after reading the following description and claims, and after viewing the drawing of a preferred form thereof, in which drawing:

Fig. 1 is a vertical section through an end portion of a plumbing fixture such as a bathtub, showing the invention applied thereto,

Fig. 2 is a front or plan view of the outlet plug operating handle and combination escutcheon plate and overflow outlet member,

Fig. 3 is a top plan view of the outlet plug shown in Fig. 1, and

Fig. 4 is a top plan view of a fragment of a portion of the operating means for the plug.

The plumbing fixture, which for the purpose of this description will be assumed to be a bathtub, is made of enameled iron or 50 vitreous ware is designated 2 and is provided

with a waste outlet orifice 3 in the bottom and preferably adjacent one end, and an overflow outlet orifice 4 preferably adjacent the top at the same end. The margin of the fixture about the waste orifice 3 is preferably bevelled off, as shown at 5, to provide a shoulder against which an outwardly tapered flange 6 of a plug seat member or spud 7 is seated. The shank 8 of the spud is threaded as shown at 9 for threaded engagement with internal threads of an elbow fitting 11 between a shoulder 12 of which and the bottom of the tub a rubber gasket or a washer 13 is disposed and clamped.

The seat member or spud fitting 7 is provided with a ground seat 14 against which a ground seat 15 of a plug 16 is adapted to seat in a substantially water-tight manner. The plug 16 is provided with a projection 17 at one side and is arranged to be disposed between a pair of spaced lugs 18 preferably integral with the flange 6 of the spud fitting. The lugs 18 and the projection 17 are drilled through for the reception of a hinge or pivot pin 19 which may be secured against displacement in any suitable manner provided it permits the plug to swing between the dotted and full line positions indicated in Fig. 1. The lower side or bottom of the plug is preferably provided with an integral projection 21 which terminates in a pair of spaced lugs 22 (one shown) between which one end of a lever or link 23 is pivotally secured on a pivot pin 24. The end of the lever or link pivoted between the lugs 22 has a portion 25 flattened off for cooperation with a flat bottom 26 of the slot between the projections or lugs 22 so that the lever cannot move beyond a substantially vertical position with respect to the plane of the plug in an anti-clockwise direction viewing Fig. 1, that is, away from the hinge. The opposite corner of this end of the lever 23 is rounded off as shown at 27 to permit the lever to swing toward the hinge 19 such as is illustrated in the uppermost dotted line position of the plug.

The overflow orifice 4 is covered on the inside of the tub or fixture by an escutcheon plate 28 which has a portion 29 struck out

to provide a gap or opening 31 and a central hollow boss 32 within which a hollow shaft 33 is journalled. This escutcheon plate is held in place by suitable screws 34 which pass into appropriate lugs (not shown) formed integral with an elbow fitting 35. Between a circumferential shoulder 36 on the fitting 35 and the back of the wall of the tub or other fixture is a rubber washer 10 or gasket 37.

The elbow fittings 11 and 35 are connected together and to a common drain pipe 38 by means of pipes 39 and 41 respectively, and a T-coupling 42. This arrangement of 15 connections from waste orifice or overflow orifice is quite common and for such reason it is not deemed necessary to go into the details of it here. The plug 16 is adapted to be raised, that is, swung about its hinge 20 to an open position by means of the lever 23, and for the purpose of operating the lever its lower end is pivotally connected as at 43 to a flexible rod and ball chain 44 similar to the chains very commonly used for 25 electric light switches and the like. The chain 44 passes through the waste pipe 39 and up the overflow pipe 41 to the outlet orifice for connection to a hand operable member. The hand operable member is the sleeve 30 or hollow shaft 33 which at its end inward of the tub or other fixture is provided with a handle 45 secured to it by a screw 46 and by splines or other means to prevent relative rotation, as will be understood. The inner 35 end of the sleeve or shaft 33 is provided with an offset portion 47 apertured as shown at 48 for passage of the balls or links of the chain 44, while a spring 49 disposed between a shoulder 51 formed on the end of the sleeve 33 and a shoulder 52 provided by the end 40 of the boss 32 serves to urge the sleeve inwardly of the fitting 35 and hold a collar 53 tightly against the escutcheon plate 28. A set screw 54 is adapted to pass through the 45 collar 53 and the sleeve 33 and engage between links of the chain, in this case, the balls thereof, to secure it to the sleeve. Preferably interposed intermediate of the ends of the chain is a spring 55 for the purpose of 50 absorbing shocks and for the purpose of providing a certain amount of resilience in case the chain should become caught.

In operation, assuming it is desired to drain water from the fixture, in this case, the 55 tub, the handle 45 is rotated either to the right or left, clockwise or anti-clockwise, which movement, due to the offset portion 47 of the sleeve 33, tends to wind up on the chain 44 and exerts a pull on it. This pull 60 on the chain 44 pulls the lever 23 to the dotted line position illustrated at 23' and the plug 16 to the dotted line position 16', as will be apparent, the tension of the spring 49 placing sufficient friction on the operating parts 65 of the handle mechanism to hold the handle

in its rotated position until it may be released. The surfaces 25 and 26 of the lever and plug cooperate during this operation to prevent the lever from swinging beyond a predetermined fixed angle with respect to the plug; 70 in the embodiment illustrated approximately 90° with respect thereto.

In case it is desired to remove débris that has accumulated in the drain or overflow pipes, or it becomes necessary to repair or 75 replace the chain 44, or it is necessary to have access to the interior of the outlet or waste orifice, it is desirable that the plug 16 be raised sufficiently entirely to clear the orifice. This is accomplished by returning 80 the handle 45 to its initial or what may be termed its zero position to release the chain and the tension on the spring 55, at the same time pulling upwardly on the plug 16 with the fingers or with a tool. Release of the 85 chain and the construction and arrangement of the end of the lever pivoted to the plug permits the plug to be raised to the position illustrated at 16'', the lever assuming the 90 position illustrated at 23''. In this position 95 access to the fitting 11 or the pipe 39 etc. may be had with practically the same ease were the plug entirely removable from the fixture. When it desired to insert a new chain, this may be more easily accomplished 95 with the plug raised to its position.

While the invention has been illustrated and described in its preferred form, it will be appreciated that it is susceptible of many changes, modifications and variations bearing little resemblance to such preferred form, without departing from the spirit of the invention or the scope of the appended claims.

We claim:

1. In combination, a plumbing fixture such as described having a waste outlet orifice, a plug seat member having a seat extending about said orifice, a waste plug secured to said member by a hinge at one side and engageable with said seat, a rigid lever pivoted at one end to the underside of said plug, means for limiting pivotal movement of said lever and plug relatively in one direction, said plug and lever being relatively movable in another direction, and reciprocable means connected with the other end of said lever and movable in one direction to engage said limiting means and raise said plug a predetermined distance from said seat, said pivotal connection of said lever permitting said plug to be raised a greater distance from its seat.

2. In combination, a fixture having a waste outlet orifice, a plug seat member having a seat extending around said orifice, a hinge on said member adjacent said seat, a waste plug hinged at one side to said hinge, a projection connected with the underside of said plug, tensioning means external of said fixture and connected with said projection, a predetermined tension on said means in one 130

direction serving to swing said plug on said hinge from said seat, and a break connection between said tensioning means and said plug whereby said plug may be swung manually to a greater distance from said seat when said tensioning means is released.

3. In combination, a fixture having a waste outlet orifice and an overflow orifice remote from and above said waste orifice, waste and overflow pipes connected to said fixture at said orifices respectively and connected with each other, a plug seat in said waste orifice, a plug adapted to seat on said seat from the interior of said fixture, a hinge securing said plug relatively to said fixture, the axis of said hinge being disposed transverse the general direction of said waste pipe and at a side of said waste orifice remote from the connection of said waste and overflow pipes, a lever pivotally connected at one end to the bottom side of said plug on an axis parallel the axis of said hinge, said lever being movable only between a position substantially at right angles to the plane of said plug and a position substantially parallel thereto with the opposite end of said lever toward said hinge, and tension means connected with said opposite end of said lever, extending through said pipes to said overflow orifice and operable thereat for swinging said plug about said hinge a distance to open said waste orifice, said plug by reason of said pivotally connected lever being adapted to be swung a greater distance about said hinge upon release of said tension means.

In witness of the foregoing we affix our signatures.
